UNITED STATES PATENT OFFICE.

ENOCH P. BLACKLEY, OF HAMLET, NORTH CAROLINA.

VALVE FOR AIR-BRAKE SYSTEMS.

1,218,362.

Specification of Letters Patent.

Patented Mar. 6, 1917.

Application filed May 31, 1916. Serial No. 100,866.

To all whom it may concern:

Be it known that I, ENOCH PEYTON BLACKLEY, a citizen of the United States, residing at Hamlet, in the county of Richmond and State of North Carolina, have invented certain new and useful Improvements in Valves for Air-Brake Systems, of which the following is a specification.

My invention relates to angle cocks for air 10 brake systems.

The object of my invention is to provide an angle cock of the type described, with means for disposing of the dust and sediment carried by the air in the flexible train 15 pipe sections of an air brake system, when the angle cock is operated to relieve the air from the flexible sections, whereby the said dust and sediment carried by the air will not fly into the operator's face.

With the above and other objects in view, the present invention consists in the combination and arrangement of parts hereinafter more fully described, illustrated in the accompanying drawings, and particularly 25 pointed out in the appended claims, it being understood that changes may be made in the form, size, proportion and minor details without departing from the spirit or sacrificing any of the advantages of the invention.

In the drawings

Figure 1 is a vertical longitudinal sectional view of the invention.

Fig. 2 is a horizontal longitudinal sectional view.

Fig. 3 is a vertical transverse sectional view.

In the drawings, 1 represents the casting of the angle cock, having the usual bore 2 therethrough, and 3 is the conical plug or valve held in place in the casting by means of the spring 4, which in turn, is held under tension by means of the cap 5 screwed into the lower end of the casting. The valve 45 may be operated by means of a wrench applied to the usual rectangular head 6 formed integral with the plug or valve 3.

Extending through the side of the casting and at right angles to the bore 2 is a port 7 50 communicating with the atmosphere.

The valve or plug 3 is provided with a bore 8 extending through the same and terminating in an upper chamber 9 and a lower chamber 10. Extending through the valve 55 or plug above the port 8 and at right angles to the same, is a port 11 opening into the

upper chamber 9. The lower chamber 10 is designed as a dust receiver for a purpose to be presently explained.

My invention operates as follows: When 60 the plug or valve is in open position the bore 8 of the plug and the bore 2 of the casting are in registration and the air in the system is free to pass through the said plug. In this position of the plug or valve, the 65 ports 7 and 11 are entirely out of use, but when the plug or valve is turned to closed position and communication cut off through the bores 2 and 8, the port 11 comes into registration with the bore 2 of the casting 70 and the bore 8 of the valve or plug comes into registration with the port 7, whereby communication is established between the atmosphere and the space back of the plug or valve 3, thereby relieving the pressure in 75 the flexible train pipe sections and permitting the ready uncoupling of the same. By reason of having the port 11 situated in the upper part of the plug or valve 3, the dust in the air as it escapes from the port 11, will 80 drop to the bottom of the said plug and settle in the chamber 10, while the air will escape through the port 7 to the atmosphere. If the port 11 were in the middle of the plug or valve and on a line with the port 7, the 85 dust carried by the air would be forced out through the port 7 with the air and into the operator's face, thereby inflicting possible injury. By having the port 7 located at the top of the valve, this difficulty is obviated. 90

What I claim is:—

1. In an angle cock for air brake systems, a casting having a central bore therethrough and a port extending through the casting at right angles to the said bore and communicating with the atmosphere, a plug in said casting having a main bore therethrough and a port extending through said plug at right angles to the main bore and located at the top of the plug, whereby when the plug is 100 closed to cut off communication through its main bore, the said main bore will register with the port in the casting and the port in the valve will register with the upper part of the bore of the casting, whereby air will 105 be relieved from behind the said plug, but dust carried by said air will be dropped to the bottom of the bore of the plug and not escape to the atmosphere.

2. In an angle cock for air brake systems, 110 a casting having a central bore therethrough and a port extending through the casting at

right angles to the said bore and communicating with the atmosphere, a plug in said casting having a main bore extending therethrough, said bore terminating in an upper and lower chamber, the said plug having a port extending therethrough at right angles to the bore, and located at the top of the plug and communicating with the upper chamber, whereby when the plug is closed to 5 cut off communication through its main bore the said main bore will register with the port in the casting and the port in the plug will register with the upper part of the bore of 10

the casting, whereby air will be relieved from behind the said plug, but dust carried 15 by said air will be dropped to the bottom of the plug and into the lower chamber therein and thereby not escape to the atmosphere.

In testimony whereof I affix my signature 20 in the presence of two witnesses.

ENOCH P. BLACKLEY.
